FOLDABLE BOX AND BLANK THEREFOR

William A. Ringler, Wayne, Pa., assignor to Carton Container Company, Philadelphia, Pa., a corporation of Delaware

Application November 25, 1932, Serial No. 644,335

4 Claims. (Cl. 229—34)

The object of this invention is to devise novel constructions of foldable blanks which can be formed from sheet material and which can be folded to provide collapsible boxes which can be quickly assembled in box formation by moving opposite portions of the blanks inwardly and folding them into the box.

A further object of the invention is to devise a novel collapsible box which can be quickly assembled by moving inwardly opposite end portions and folding the free end or ends into the box to form a double bottom, the upper bottom section being locked in a novel manner to retain it in assembled position.

15 A further object of the invention is to devise a novel box which can be formed from a single sheet and folded to form collapsible side walls which are expanded when opposite side portions are moved inwardly, and such side portions are folded around the juxtaposed side walls and are secured in position in a novel manner.

With the above and other objects in view, as will hereinafter clearly appear, my invention comprehends a novel blank and a novel collapsible box which can be formed therefrom.

25 It further comprehends a novel box formed from a single sheet which is foldable to form collapsible sides which are expanded by folding two end portions around opposite sides, and the end portions are locked with juxtaposed box portions to maintain the box formation.

Other novel features of construction and advantage will hereinafter more clearly appear in the detailed description and the appended claims.

35 For the purpose of illustrating the invention, I have shown in the accompanying drawings typical embodiments of it, which, in practice, will give satisfactory and reliable results. It is, however, to be understood that the various instrumentalities of which my invention consists can be variously arranged and organized, and my invention is not limited to the exact arrangement and organization of these instrumentalities as herein set forth.

45 Figure 1 is a plan view of a blank from which a box embodying my invention can be formed.

Figure 2 is a plan view of the box in collapsed condition.

Figure 3 is a perspective view of the assembled box.

50 Figure 4 is a section on line 4—4 of Figure 3.

Figure 5 is a plan view of a blank embodying my invention.

Figure 6 is a section on line 6—6 of Figure 9.

55 Figure 7 is a section on line 7—7 of Figure 9.

Figure 8 is a perspective view of a partially completed box, formed from the blank seen in Figure 5.

Figure 9 is a perspective view of a box formed from the blank seen in Figure 5.

Figure 10 is a plan view of another form of box blank embodying my invention.

Figure 11 is a plan view of a partially completed box formed from the blank seen in Figure 10.

Figure 12 is a plan view of Figure 11 with the 10 side walls collapsed.

Figure 13 is a perspective view of a partially completed box formed from the blank seen in Figure 10.

Figure 14 is a plan view of another form of 15 blank embodying my invention.

Figure 15 is a perspective view of a box formed from the blank seen in Figure 14.

Similar numerals of reference indicate corresponding parts.

20

Referring to the drawings:

Referring first to the embodiment seen in Figs. 1 to 4 inclusive, 1 designates a blank embodying my invention which comprises a single sheet of material, such as, for example, paper, cardboard, 25 or other desired material. The blank has extending transversely across it the weakened lines 2, 3, 4, 5, 6, and 7, which contribute to form a bottom flap 8, an end flap 9, an end wall 10, a bottom wall 11, a second end wall 12, a second 30 end flap 13 and a second bottom flap 14. The bottom flap 8 is shorter than the end flap 9 as shown in Fig. 1. The flap 14 at the opposite end of the blank has a marginal portion removed as at 15 thus forming marginal locking projections 35 28 and 29 as will hereinafter be clearly explained.

The blank is provided with a longitudinally extending weakened line 16 which defines a side wall 17. A slit 18 forms a continuation of the weakened line 16 and contributes to form a 40 locking tab 19 having a diagonally directed fold line 20 forming a bellows section 21. The tab 19 is provided with a locking slot 22. The blank is also provided with a slit 23 forming a continuation of the weakened line 16 and contributing 45 to form a locking tab 24 having a diagonally directed fold line 25 forming a bellows section 26. The locking tab 24 is provided with a locking slot 27.

The blank is also provided with a longitudinally extending weakened line 30 which defines a side wall 31. A slit 32 forming a continuation of the weakened line 30, contributes to form a locking tab 33 having a diagonally directed fold line 34 forming a bellows section 33. The tab 50 55

33 is provided with a locking slot 36. A slit 37 forms a continuation of the fold line 30 and contributes to form a locking tab 38 having a diagonally directed weakened line 39 forming a bellows section 40. The locking tab 38 is also provided with a locking slot 41.

The slots 22, 27, 36, and 41 are directed in the same direction so that when the side walls 17 and 31 are bent upwardly the tabs 19 and 33 can be turned inwardly and interlocked and the inwardly turned tabs 24 and 38 so as to retain the side walls 17 and 31 in erect assembled position. It is, of course, to be understood that the locking tabs 19 and 33, and the locking tabs 24 and 38 may be secured together by adhesive or any other desired manner.

Due to the provision of the diagonally directed fold lines 20, 25, 34, and 39, it will be apparent that the side walls and end walls can be collapsed as shown in Fig. 2 so that the end flap 13 and the bottom flap 14 and also the bottom flap 8 and the end flap 9 can be folded over to form a flat collapsible package for shipping.

When the user desires to form the box he takes the collapsed blank as shown in Fig. 2, and lifts the end walls 10 and 12 upwardly, thereby causing the locking tabs 19 and 24 and the side walls 17 and 31 to be also erected. The end flap 9 is now bent over the locking tabs 19 and 33, so that it is disposed vertically adjacent the inside face 2 of the locking tabs 19 and 33 with the locking flap 8 seating over the bottom wall 11.

The end flap 13 is then bent over the locking tabs 24 and 28 and folded downwardly to seat against the inside face thereof, and the bottom locking flap 14 is seated over the bottom wall 11. The marginal locking projections 28 and 29 will extend around the ends of the bottom flap 8, as will be clearly understood by reference to Fig. 3. This forms a very strong box having a double bottom and two opposite walls have a three-ply construction as is apparent. The bottom flap 8 and the bottom flap 14 form locking flaps and an auxiliary bottom.

Referring now to Figs. 5, 6, 7, 8, and 9, there is shown a blank 42 forming another embodiment of my invention, which blank is formed from a single piece of sheet material. The blank has extending laterally across it the fold lines 43, 44, 45, 46, 47, and 48, which define the bottom flap 49, end flap 50, end wall 51, bottom 52, a second end wall 53, a second end flap 54 and a second bottom flap 56.

The blank also has longitudinally extending fold lines 56 and 57 which define the side wall 58 and side flap 59. A slit 60 forms a continuation of the fold line 56 and contributes to form an end tab 61 so that the bottom flap 49, end flap 50 and end wall 51 are separated from the tab 61. It will be seen that the marginal edges of the flap 50 and wall 51 are cut away on an incline, as at 62. The tab 61 has a diagonally extending weakened line 63 and the weakened line 45 extends through the side flap 59, to form bellows sections 64 and 65.

In a similar manner, a slit 66 forms a continuation of the weakened line 56 and contributes to form a tab 67. The marginal portion of the end wall 53 and end flap 54 are cut away at an angle, as at 69. The tab 67 has a diagonal weakened line forming bellows section 64 and 65.

The blank is also provided with the longitudinally extending fold lines 70 and 71 which define the side wall 72 and side flap 73. A slit 74 contributes to form the tab 75. The tab 75 has a

diagonally directed fold line 76 which contributes with the line 45 to form bellows sections 77 and 78. The marginal portions of the end flap 50 and end wall 51 are cut away at an angle, as at 79. A slit 80, forming a continuation of the weakened line 70 contributes to form a tab 81. The tab 81 is provided with a diagonally directed fold line 83 which contributes with the lines 46 to form bellows sections 84 and 85. The end wall 53 and end flap 54 have their marginal edge 10 cut away as indicated at 86. The tabs 75 and 81 are provided with adhesive 68 and 82 respectively, extending over their entire height.

In assembling the container the side flap 59 is folded over the side wall 58 and the side flap 15 73 is folded in a similar manner inwardly over the side wall 72. The bellows sections 77 and 78 are thus brought together, as well as the bellows sections 65 and 64. The tabs 75 and 61 are then bent laterally and secured together over 20 their entire height by means of the adhesive 68 and the tabs 67 and 81 are bent laterally and secured together over their entire height by the adhesive 82. The end wall 51 is bent upwardly and the end flap 50 is bent over the wall 51, the 25 bottom flap 49 being bent downwardly so that its opposite marginal portions will extend under and be retained by the side flaps 59 and 73.

In a similar manner the end wall 53 is folded upwardly. The end flap 54 is then bent inwardly 30 over the end wall 53 and the bottom flap 55 bent downwardly so that its opposite marginal portions extend beneath the downwardly deflected side flaps 59 and 73 and lock the end wall 53, end flap 54, bottom flap 55, and tabs 67 and 81, in 35 assembled position.

It will thus be seen that a double thickness of the bottom is provided, with two opposite sides of double thickness and the other two opposite sides of quadruple thickness so that a very strong box 40 is provided.

It will be understood that this box is collapsible in a similar manner to that already described in reference to the other figures of the drawings due to the provision of the bellows sections 64, 65, 77, 45 78, 84, and 85.

Referring now to Figs. 10, 11, 12, and 13, there is shown another form of blank 87 embodying my invention. This blank is provided with transversely extending fold lines 88, 89, 90, 91, 92, 93, 50 94, which contribute to form a bottom flap 95, an end flap 96, an end wall 97, a bottom wall 98, a second end wall 99, a second end flap 100, a second bottom flap 101 and a section 102. The section 102 is provided with a cut out 103. 55

The blank is also provided with a fold line 104 which defines a side wall 105. A slit 106 forms a continuation of the fold line 104 and contributes to form a tab 107 having a diagonally directed fold line 108 which contributes to form 60 a bellows section 109. The tab 107 has a slit 110 which opens through its inner side edge. A fold line 111 contributes to form a tab 112 which is provided with a diagonally directed fold line 113 which contributes to form a bellows section 114. 65 The tab 112 is provided with a slot 115 which opens through its inner marginal edge.

In a similar manner, the blank is provided with a fold line 116 which contributes to form a side wall 117. A slit 118 forming a continuation of 70 the weakened line 116 contributes to form a tab 119 having a diagonally directed fold line 120 which contributes to form a bellows section 121. The tab 119 has a slit 122 which opens through its outer marginal edge. A slit 123 forming a 75

continuation of the fold line 116 contributes to form a tab 124 having a diagonally directed weakened line 125 which contributes to form a bellows section 126. The tab 124 has a slot 127 opening through its outer side edge. The tab 124 has a slot 127 opening through its outer side edge.

In this form of my invention the box is formed by folding the side walls 105 and 117 upwardly 10 and folding the tabs 107 and 119 and the tabs 112 and 124 inwardly, the tabs 107 and 119 interlocking with each other, and the tabs 112 and 124 interlocking with each other so that the parts appear as seen in Fig. 11. Due to the provision 15 of the diagonally directed fold lines 108, 113, 120, and 125, the side walls can be collapsed as shown in Fig. 12, so that a flat collapsible package can be formed.

When the box is assembled the end walls 97 and 20 99 are bent upwardly thereby causing the side walls 105, 117 and the tabs 107 and 119 and 112 and 124 to assume the position seen in Fig. 11. The end flap 96 is then bent over the tabs 107 and 119 and the bottom flap 95 positioned along the 25 bottom wall 98. The end flap 104 is then bent over the tabs 112 and 124 and the bottom flap 101 positioned along the bottom wall 98.

In this form of collapsible box the bottom has double walls, two opposite side walls are of single- 30 ply construction and the other two opposite side walls are of three-ply construction.

In the form of my invention shown in Figs. 14 and 15, the blank 128 comprises a single piece of sheet material having the transversely extending 35 fold lines 129, 130, 131, 132, 133, and 134, which define a bottom flap 135, an end flap 136, an end wall 137, a bottom wall 138, a second end wall 139, a second end flap 140 and a second bottom flap 141. A fold line 142 extends longitudinally 40 of the blank and defines a side wall 143. A fold line 144 defines a side flap 145, which had its corners cut away as at 146.

A fold line 147 contributes to form a tab 148 having a diagonally directed fold line 149 which 45 contributes to form a bellows section 150. At the opposite ends of the blank a fold line 151 defines a tab 152 having a diagonally directed fold line 153 which contributes to form a bellows section 154. A fold line 155 contributes to form 50 a side wall 156, and a fold line 157 contributes to form a side flap 158 having the corners cut away as at 159. A slit 160 contributes to form a tab 161 having a diagonally disposed fold line 162 which contributes to form a bellows section 163. 55 A slit 164 contributes to form a tab 165 having a diagonally directed fold line 166 which contributes to form a bellows section 167.

In forming the box the tabs 148 and 161 and the tabs 152 and 165 are bent laterally and 60 secured together. The side flap 145 is turned inwardly against the inside face of the side wall 143 and secured to it in any desired manner, for example, by a clip 168. In a similar manner, the side flap 158 is bent inwardly over the side wall 156 and secured to it by a clip 168. The end wall 137 is bent upwardly and the end flap 136 is bent over the tabs 148 and 161. The opposite 65 ends of the bottom flap 135 extend beneath the shoulders formed by the cut outs 146 and 159 so that they are locked in place. In a similar manner the end wall 139 is bent upwardly and the end flap 140 is bent over the tabs 152 and 165 and the bottom flap 141 is bent downwardly 70 to engage the bottom wall 138 and its free ends

engage the shoulders formed by the cut outs 146 and 159.

In this form of my invention a box is formed in which two opposite side walls are of double thickness and the other two opposite side walls 5 are of triple thickness, the bottom wall being of single thickness.

In all the forms of my invention as herein shown, I form from a single blank of sheet material a collapsible box in which the sides are collapsed and by moving two walls towards each other the side walls of the inner box are raised vertically and the free marginal portions of the blank are folded over and preferably interlocked 10 with walls of the box.

I am aware that it has heretofore been proposed in the Gross Patent No. 1,690,109 to make a collapsible or knockdown box in which there are connections between the side flaps and end flaps for raising the side flaps and holding them in 20 operative position when the end flaps are raised. My present invention clearly differentiates from such construction since in all of the embodiments herein shown the side flaps and end flaps are not connected, and it is the pressure of the foldable end flaps when the ends of the blank are raised which forms the sole means for expanding the collapsed sides into their perpendicular 25 positions.

It will now be apparent that I have devised 30 new and useful foldable boxes and blanks therefor which embodies the features of advantage enumerated as desirable in the statement of the invention and the above description, and while I have, in the present instance, shown and described 35 preferred embodiments thereof which will give in practice satisfactory and reliable results, it is to be understood that these embodiments are susceptible of modification in various particulars without departing from the spirit or scope of the 40 invention or sacrificing any of its advantages.

For the purpose of clarity and convenience of reference, certain of the upstanding walls of the containers have been designated as "side walls" and others as "end walls" and corresponding walls 45 in each modification have been similarly designated. Since any desired relative lengths of the upstanding walls may be selected without departing from the invention, it is to be understood that the expressions "end wall" and "side wall" 50 are not to be taken as designations of the relative lengths of the walls, and that the "end wall" may be either longer or shorter than the "side wall".

Having thus described my invention what I 55 claim as new and desire to secure by Letters Patent, is:

1. A collapsible box including a bottom wall, side walls connected with the bottom wall, end walls connected with the bottom wall, side locking tabs connected with the side walls, end flaps connected with the end walls and foldable inwardly, and a bottom flap connected with one of said end flaps, said side locking tabs having creased lines to provide for the collapsing of the 60 side locking tabs, said bottom flap when positioned to overlie said bottom wall extending beneath the juxtaposed end flap.

2. A collapsible box, including a bottom wall, side walls, side locking tabs connected with the 70 side walls to form a four-wall construction rising from said bottom wall and having weakened lines to render such construction collapsible, outer end walls connected with the bottom wall, inner end flaps connected with said outer end walls, a bot- 75

tom locking flap connected with one of said inner end flaps and having its free end extending beneath the juxtaposed inner end flap at the opposite end of the box when folded against said bottom wall.

3. A box adapted to be shipped and stored in collapsed knockdown condition and set up by the user, including a bottom wall, end walls, end flaps extending therefrom, collapsible side walls, tension tabs connecting said side walls, fold lines extending across said tabs permitting collapse of said side walls and said tabs, a compression flap hinged to each of said end walls adapted to be manipulated to engage said side walls and co-10 operate with said tension tabs to retain the side walls in rigid erect containing position, and a bottom flap hinged to one of said end flaps and

having its free end extending beneath the juxtaposed end flap at the opposite side of the box when folded against said bottom wall.

4. A collapsible box, including a bottom wall, a plurality of upstanding walls extending from the edges of said bottom wall, side locking tabs connecting said upstanding walls to form a four-wall construction rising from said bottom wall and having weakened lines to render such construction collapsible, flaps connected with certain of said upstanding walls, a bottom locking flap connected with one of said flaps and having its free end extending beneath the juxtaposed flap at the opposite side of the box when folded against said bottom wall.

15 WILLIAM A. RINGLER.
